UNITED STATES PATENT OFFICE.

MICHAEL JOSEPH McLAUGHLIN, OF ST. LOUIS, MISSOURI.

METHOD OF MAKING ORNAMENTAL PLAQUES.

1,382,925.

Specification of Letters Patent. Patented June 28, 1921.

Application filed July 25, 1918. Serial No. 246,760.

To all whom it may concern:

Be it known that I, MICHAEL J. McLAUGHLIN, a citizen of the United States, residing at St. Louis, in the county of St. Louis and 5 State of Missouri, have invented certain new and useful Improvements in Methods of Making Ornamental Plaques, of which the following is a specification.

This invention relates to a method for 10 making ornamental plaques and similar articles in which a sheet of paper or similar material bearing a suitable inscription is mounted on a suitable backing for the purpose of displaying the inscription.

15 One of the main objects of the invention is to provide a method by means of which ornamental plaques and similar articles may be readily cast from plastic material so as to provide a strong and durable mounting 20 for the picture or inscription to be displayed while presenting a neat appearance.

A further object is to provide a method by means of which plaques may be readily produced at small cost and with but little 25 work, no expert skill being required for making the plaques.

Another object is to provide means whereby a plaque may be formed in which a transparent covering for the picture to be displayed is tightly secured in the body of the 30 plaque, a suitable frame being formed about the edge portion of the covering so as to give the appearance of a picture framed in the ordinary manner.

35 Further objects will appear from the detailed description.

This invention is intended more particularly as an improvement over the method set forth in my United States application, 40 Serial #87,263, entitled ornamental plaques and method of making the same, filed March 28th, 1916, and allowed December 20th, 1917. In this improved form of my invention, the sheet of paper upon which the 45 picture or inscription to be displayed is printed, or painted, is dampened and placed upon a smooth non-porous surface, face downward, after which the backing and body portion of the plaque are cast of suitable 50 plastic material over and about the moistened sheet of paper so as to embed and brace and support the paper, and display the picture or inscription to advantage.

In the accompanying drawing which is 55 illustrative of the invention,

Figure 1 is a top plan view of means embodying the invention.

Fig. 2 is a sectional detail on the line 2—2 of Fig. 1.

Fig. 3 is a front view of a plaque constructed in accordance with the invention. 60

Fig. 4 is a sectional view of a modification.

Fig. 5 is a front view of a plaque constructed in accordance with a modification. 65

Fig. 6 is a sectional detail on the line 6—6 of Fig. 5.

Fig. 7 is a sectional detail of a modification showing the parts on a larger scale.

In carrying my invention into effect, I secure a sheet of smooth high polished plate glass 1 of relatively great thickness, (about a quarter of an inch thick,) upon a supporting table 2, which is mounted in a perfectly level or horizontal position. The 75

upper surface of this glass 1 is then thoroughly cleaned and polished to remove all dust, specks, and foreign matter therefrom. The sheet of material paper 3, or other upon which the picture to be mounted is painted 80 or printed is then cut to the required size and thoroughly moistened, after which it is placed upon the upper surface of the sheet of glass 1 face downward. The paper 3 is then smoothed or rubbed gently so as to remove all air bubbles therefrom. After this has been done, if the sheet of paper is of 85

rectangular configuration, four pieces 4 of highly polished steel are placed about the sheet of paper with ends in contact so as to 90 form an inclosing frame disposed in concentric spaced relation to the paper; this frame being composed of a plurality of members which may be readily and easily disassembled. A suitable mixture 5 of plastic 95

material, such as a mixture of plaster-of-Paris and water is then poured into the molding frame formed by the pieces of steel which have been placed together, the material flowing over and about the sheet of 100 paper which adheres closely to the upper surface of the supporting sheet of glass.

Due to the fact that the under face of the sheet of paper 3 is in close contact with the upper surface of the sheet of plate glass 1, 105 none of the plastic material 5 will flow between the paper and the glass, but this material will flow about the edge portions of the paper so as to cause this paper to be embedded in the body portion of the plaque 110

115

formed by the plaster. After this plaster has been poured into the frame, any suitable hanger 6 may be embedded in the plaster after which it is permitted to set for 5 approximately one-half an hour. After the plaster has become sufficiently firm, the pieces of steel may be readily removed from the same, after which the plaque 4 is moved slightly so as to be disengaged from the 10 surface of the sheet of plate glass, the plaque thus formed being then trimmed to remove all projections or ragged edges by means of a sharp knife or suitable instrument.

The plaster which is cast in the frame 15 forms a substantially rectangular block which constitutes the body of the plaque, the sheet of paper bearing the picture or inscription to be displayed being embedded in one face of this block so as to be supported and protected thereby. In addition, the plaster which flows between the pieces of steel forming the casting frame, and the edges of the sheet of paper constitutes an inclosing band or frame extending about 20 the picture so as to display the same to advantage, this frame also serving to prevent detachment of the paper from the plaster.

Where it is desired to provide a transparent covering, such as a sheet of glass, for the 30 picture, the above described method is slightly varied. In this case, the sheet of glass 7 which it is desired to use as a protective covering for the picture is supported a short distance above the top surface of the 35 supporting sheet of plate glass 1, by means of a sheet of card-board 8 or other suitable material placed beneath the same. This sheet 8 should, preferably, be somewhat smaller than the sheet 7 of glass, which it 40 is desired to use as a covering. If it is desired to mount a picture six inches by ten inches, of rectangular outline, the protecting sheet of glass may be cut of this size, a sheet 8 of cardboard $5\frac{3}{4}'' \times 9\frac{3}{4}''$ being placed 45 beneath the glass 7 so as to support the same a short distance above the upper surface of the supporting sheet of plate glass. Preferably, this card-board 8 should be dampened so as to fit tightly against the upper 50 surface of the plate glass and the under surface of the sheet 7 of framing glass. After the sheet 7 of framing glass has thus been supported above the upper surface of the plate glass 1, a frame 4 may be formed 55 about the sheet of framing glass 7 by placing bars of steel about the same in concentric spaced relation in the manner previously described, the picture 3 or inscription to be displayed being first dampened and

placed upon the upper surface of the sheet 60 of framing glass 7 face down in the manner described in connection with the first method stated. After the frame has thus been formed, a suitable plastic mixture 5, such as a mixture of plaster-of-Paris is 65 poured into the frame so as to flow over and about and under the sheet of framing glass. As the sheet 8 of cardboard which supports this glass 7 is approximately $\frac{1}{2}$ " less in 70 length and breadth than the glass, this card board 8 will leave a space of approximately $\frac{1}{4}$ " in width extending the full distance about the framing glass. The plastic mixture will flow about and under the sheet of glass 7 so as to fill in this space, thus forming 75 a frame which completely incloses the edge portion of the glass 7 so as to secure it in the body of the plaque. After the plaster has set sufficiently, the pieces of steel forming the molding frame are removed, 80 after which the sharp blade of a knife or any other suitable instrument may be inserted into the sheet of card board 8 which may be lifted away from the sheet of framing glass, the glass 7 being inclosed within 85 a frame corresponding in thickness to the thickness of the card board. Of course, any card board of suitable thickness or several thicknesses of card board may be employed, 90 if desired, to produce a frame of any desired depth or thickness. The plaque produced in this manner gives the appearance 95 of a picture being mounted in a white border or frame, and the picture being hermetically sealed to the glass. Of course, the border or frame portion of the plaque extending about the glass may be gilded or painted any suitable or desired shape to give the appearance of a frame of ordinary construction, if preferred.

Having thus described my invention, what I claim as new and desire to secure by Letters Patent is.—

A process of making an ornamental plaque comprising placing the face of the ornamentation upon a fixed polished surface and building the sides of the mold upon said surface around the ornamentation and casting the plaque in said mold in the usual manner, and then removing the cast plaque by first removing the sides of the mold and then the plaque from said surface.

In testimony whereof I affix my signature in presence of two witnesses.

MICHAEL JOSEPH McLAUGHLIN.
